INVALID LIFT

Charles H. Welch, Auburn, Wash.

Application March 29, 1947, Serial No. 738,099

5 Claims. (Cl. 5—86)

1

This invention relates to improvements in what may be called "invalid lifts" and it has reference more particularly to apparatus adapted for use in hospitals, or like places, for the lifting of an invalid from or into a bed, or for carrying a person while sick or under the influence of an anesthetic from a bed to an operating table, or vice versa.

It is the principal object of this invention to provide a device of the above kind that may be rolled along a floor, and brought directly over the bed or table on which the person is laying, or is to be laid, and which is equipped with coacting sets of tong-like supports, adapted to be swung from an open position to a position closed beneath a person lying on the bed or table, as a lifting means, and then to be bodily elevated, thus to lift the person clear of the bed and to support him for transportation to a place of rest; the supports being operable to release the patient easily and without injury, merely by lowering them to the bed and then opening them apart.

It is also an object of this invention to provide a lift of the above stated kind that may be easily handled by one person and which may be adjusted as required to adapt it to its various uses for persons of various size and beds of different height.

Other objects of the invention are to be found in the details of construction of the various parts of the device, in their combination and in their mode of operation, as will hereinafter be fully described.

In accomplishing these and other objects of the invention, I have provided the improved details of construction, the preferred forms of which are illustrated in the accompanying drawings, wherein—

Fig. 1 is a side elevation of an invalid lift embodied by the present invention.

Fig. 2 is an end elevation of the same, showing its relationship to a bed when positioned for lifting a person therefrom.

Fig. 3 is a sectional detail showing the gearing used in lifting and lowering the patient carrying means or supports; the section being taken on line 3—3 in Fig. 2.

Fig. 4 is a sectional detail, taken on line 4—4 in Fig. 2, showing the gearing whereby the patient supports may be opened apart and closed together.

Fig. 5 is an enlarged showing, in end view, of the patient carrying supports and their actuating gearing.

Fig. 6 is a sectional detail of the supporting

2

bearing and gearing of the supports at one end of the frame.

Fig. 7 is an enlarged elevation of the bearing and its lifting rack.

Fig. 8 is a perspective view of parts of one of the patient lifting members.

Referring more in detail to the drawings—

It is the intent that the present device be of such size that it may be moved easily between rooms of a hospital through doorways of ordinary size, and adapted to pick up a person from a hospital bed of ordinary height. Also, it is intended to accommodate persons of average weight and of average size. However, the size of the device and the relative proportions of its parts might be varied within a certain range of limits without departing from the spirit of the invention.

In its present preferred form, the device comprises a main frame structure made up of opposite end frames 10 and 10 that are joined rigidly in upright, spaced relationship by horizontal connecting rods 11. The two end frames are substantially alike in size and construction and by reference to Fig. 2, it will be understood that each is made up of tubular members, and comprises a vertical post 12, at one side thereof, that is rigidly and securely fixed at its lower end in a fitting 13 from which a horizontal member 14 extends in a transverse direction; that is, directly toward the opposite side of the device. At the outer end of the member 14 is a fitting 15 which mounts therein a frame supporting caster wheel 16. A similar supporting caster 16' is mounted in fitting 13. With both of the end frames 10 and 10 so equipped with supporting casters, the device may be easily rolled in any direction upon a floor and easily brought to loading or unloading position over a bed or the like.

Secured to the upper end of the post 12 of each end frame, by means of a pipe fitting 17, is a transverse frame structure that comprises parallel and vertically spaced top and bottom members 18 and 19, that are rigidly joined at their outer ends by a vertical pipe member 20, and are rigidly joined at their inner ends by a vertical member 21 which is applied at its lower end to the fitting 17; the member 21 being, in effect, a continuation of the corresponding post 12. The two end frames 10 and 10, as so constructed, are rigidly joined by three of the horizontal rods or tubes 11, and it is shown in Figs. 1 and 4 that one of these tubes joins the end frames directly between the lower end fitting 13. Another cross rod 11 joins the frames directly between the upper ends of the

posts 21, and the third cross rod joins the frames directly between the fittings 17 that are applied to the upper ends of the posts 12. All parts of the main frame are thus rigidly and securely united.

It is to be understood that the two transverse frame structures constituting the upper portions of the opposite end frames, are supported at such elevation that they may be positioned directly over a bed of the height and kind ordinarily used in hospitals, with some clearance, as has been illustrated in Fig. 2, wherein a bed has been indicated in dotted lines and designated by reference numeral 25. The frame may be longer than a bed or it may be shorter without detriment to its use.

Extended between the two lateral or transverse portions of the end frames, are the members provided for lifting and holding the patient while being moved, and which I have referred to herein as the patient supports. These members are shown in plan view in Fig. 4 as comprising a pair of parallel opposite side rods 30 and 30 extended horizontally between the end frames. Each rod is equipped at its opposite ends with hanger or supporting arms 31, and each of these is supported at its inner end by a trunnion 31x about which it may swing pivotally. These trunnions are contained in bearing housings 32 and 32 in opposite end frames 10 and 10.

As observed in Figs. 2 and 4, each of the bearing housings 32 is contained for vertical adjustment between spaced, vertical guide rods 34—34 which are fixed at their upper and lower ends respectively to the horizontal tubes 18 and 19 of the corresponding end frames. The trunnions 31x of the arms 31 at corresponding ends of the device, are mounted in horizontally spaced relationship in a bearing housing 32, and the trunnions of the same bearing are equipped with gear wheels 35 in intermeshing relationship, as seen in Fig. 5, whereby the two supports may be held in proper functional relationship, and caused to swing in unison between open and closed positions. A shaft 40 extends between the housings 32 and 32 and is rotatably contained therein, and fixed to this shaft are gear wheels 42 and 42 that mesh with gears 35 at each end of the device as seen in Fig. 4.

At one end, the shaft 40 is equipped with a bevel gear 43 and this operates, as seen in Fig. 4, in driving mesh with a bevel gear wheel 44 on a shaft 45 that is supported revolvably in a housing 46 and extends to one side of the device where it has connection, through gearing indicated at 47, with a hand wheel 48 for the manual adjusting of the two patient supports between open and closed positions. The housing 46 is fixed to the bearing block 32 at the end of the device, and may move up and down with the block.

It will be understood that, through the gearing above described, the turning of the hand wheel 48 will impart rotation to shaft 40, and this, through the gears 42 thereon, and gears 35, will cause outward or inward swinging of the arms 31 and a like swinging of the horizontal rods 30—30 from or toward each other.

Fixed on the rods 30 and 30, at spaced intervals therealong, are thin, inwardly directed fingers 50, adapted to be moved from positions at opposite sides of a patient, to positions beneath the patient when lying on a bed or the like. When the supports are in what may be called a closed position, as seen in full lines in Figs. 2 and 5, the fingers 50 as extending inwardly from the op-

posite rods 30—30, will overlap each other, as shown in Fig. 4, and when the supports are opened apart, as indicated in dotted lines in Figs. 2 and 5, the ends of the fingers at opposite sides are substantially spaced apart and the fingers are substantially vertical; that is, the fingers of the two rods 30—30 are spaced a distance ample for a person to lie between them.

The patient supports, constituted by the rods 30—30, arms 31 and fingers 50, may be bodily adjusted between lowered and raised positions by the vertical movement of the bearing housings 32 and 32. This adjustment of housings may be effected by means which I have shown best in Figs. 2, 3 and 7, wherein it is shown that each housing has a vertical rack bar 60 fixed thereto at its lower end and extended upwardly from the housing and slidably through a bearing housing 61 fixed to the top member 18 of the corresponding side frame. Extended between the bearings 61 is a horizontal shaft 62 and fixed on this, as in Fig. 3, are gears 63—63 in mesh with the racks 60—60. At one end of shaft 62 is a bevel gear wheel 64 and this meshes with a bevel gear 65 on a shaft 66 carried in a housing 67 that is fixed to the end frame. A hand wheel 68 is connected to shaft 66 by gearing as indicated at 70.

Through this arrangement of gearing, turning of the hand wheel 68 will cause an upward or downward adjustment of both racks and will thereby cause a corresponding raising or lowering of the housings 32 and 32 to raise or lower the patient supports accordingly.

In Fig. 8, I have shown that the cross rods 30 and 30 are tubular and that the fingers 50 are fixed thereto. The fingers which are at the ends of the tubes have knurled hub ends, as at 50x, and these surfaces engage against similarly knurled surfaces 31x on the ends of the suspending arms 31. Rods 30x extend centrally through the tubes 30 from end to end thereof, and through their suspending arms 31 and have lock nuts, as at 30n, applied to the ends of the rods to clamp the arms tightly against the knurled end surfaces of the end fingers, thus to hold the tubular parts 30 against any relative turning. By loosening the nuts 31n, the knurled surfaces may be sufficiently disengaged to permit of any desired turning adjustment of the rods 30 for obtaining finger adjustment of that kind indicated by the dotted line showing of the fingers in Fig. 5.

With the device so constructed, it would be used as follows:

Assuming that the patient is to be moved from a bed; the device is rolled into position as seen in Fig. 2 with the patient supports opened apart, as shown in dotted lines in Fig. 5 and elevated to position to adequately clear the patient. Then with the device in place, the patient lifting structure is lowered to proper position by turning hand wheel 68 and, then the wheel 48 is rotated to cause the lifting fingers 50 to be projected beneath the patient from opposite sides. Then the carrying structure is elevated by turning wheel 68 to lift the patient clear of the bed. The device is then pushed to the place where patient is to be placed.

Having thus described my invention, what I claim as new therein and desire to secure by Letters Patent, is—

1. A device of the character described comprising a mobile structure including opposite end frames, a pair of transversely spaced, horizontal rods extended lengthwise of the structure between said end frames, a pair of arms mounted

by each of the opposite end frames with ends adapted to be swung toward and from each other in a vertical plane and transversely of the structure, said arms supporting said rods from their swinging ends, means for actuating said arms in unison to swing said rods from and toward each other between inner and outer limits of travel, fingers fixed rigidly to said rods and adapted by the swinging of said rods from their outer limits of travel to their inner limit to be brought from a spaced apart relationship to an intermeshing relationship for the support of a person thereon between the rods.

2. A device as recited in claim 1 including also bearings mounted in the opposite end frames for the pivotal mounting of the said pairs of arms therein and means operable for the raising and lowering of said bearings in unison.

3. A device of the character described, comprising a mobile structure including opposite end frames, a bearing housing mounted in each end frame for vertical adjustment therein, a pair of arms, with trunnions at upper ends rotatably mounted in each of said bearing housings, and adapted to be swung on said trunnions from and toward each other at their lower ends, a pair of transversely spaced, horizontal rods extended lengthwise of the structure and fixed at their ends to the swinging ends of corresponding arms of the said pairs of arms, a gear wheel fixed on each of the trunnions, an actuating shaft extended lengthwise of the structure and rotatably mounted by said bearing housings; gears fixed on said shaft meshing with the gears on said trunnions, and means for rotating said shaft to effect an inward or outward swinging adjustment of said longitudinal rods from and toward each other, and fingers fixed on said longitudinal rods and adapted by the swinging adjustment thereof to be moved between spaced apart and intermeshed relationship.

4. A device of the character described, comprising a mobile structure including opposite end frames, a bearing housing mounted in each end

frame for vertical adjustment therein, a pair of arms, with trunnions at upper ends rotatably mounted in each of said bearing housings, and adapted to be swung on said trunnions from and toward each other at their lower ends, a pair of transversely spaced, horizontal rods extended lengthwise of the structure and fixed at their ends to the swinging ends of corresponding arms of the said pairs of arms, a gear wheel fixed on each of the trunnions, an actuating shaft extended lengthwise of the structure and rotatably mounted by said bearing housings; gears fixed on said shaft meshing with the gears on said trunnions, and means for rotating said shaft to effect an inward or outward swinging adjustment of said longitudinal rods from and toward each other, and fingers fixed on said longitudinal rods and adapted by the swinging adjustment thereof to be moved between spaced apart and intermeshed relationship, and means for effecting a raising and lowering adjustment of said bearing housings in unison.

5. A device as recited in claim 3 including also a rack bar fixed to and extended vertically from each bearing housing, a shaft extending horizontally between the opposite end frames, gears on said shaft meshing with said rack bars; and means for rotating said shaft to effect the raising and lowering of said bearing housing in unison for the raising and lowering of said longitudinal rods, and means for securing the said shaft against turning.
